HAIR CURLER

Gennette Unwin, Schenectady, N. Y., assignor to
 Plate Manufacturing Company, Detroit,
 Mich.

Application May 28, 1935, Serial No. 23,875

7 Claims. (Cl. 132—33)

This invention relates to improvements in hair curlers and it is the general object of the invention to provide a curler which can be easily manipulated and exert a uniform clamping action 5 on the hair.

In the curling of hair it is customary to clamp the ends of a lock of hair between curling and clamping elements and then rotate them to wind up the hair to a position as close to the head 10 as possible, after which a bobbie pin or the like is used to hold the curled hair and the curler is removed. It is desirable that the clamping action be uniform throughout the length of the curling element and it is an important object of 15 my present invention to provide a clamp so mounted as to move uniformly toward and from the curling element, preferably by a parallel motion, thereby permitting the invention to be used either with fine or coarse hair.

It is desirable to provide the curling element 20 with a handle or the like by which it may be manipulated and it is a further object of the invention to mount the operating parts for the clamp within the handle.

It is another object of my invention to provide 25 a hair curler which can be manipulated with one hand, this result being accomplished by a sliding head or the like operatively connected to the clamp so that movement of the head relatively to the curling element will effect movement of the clamp. This result may be accomplished by 30 means of an inclined surface operatively interposed between the curling element and clamp and rendered effective by longitudinal movement 35 of the head to space the clamp from the curling element. The head may conveniently be located at the end of the curler in an unobstructed position where it may easily be reached.

With these and other objects in view which 40 will appear as the description proceeds, my invention resides in the combination and arrangement of parts hereinafter described and set forth in the claims.

In the accompanying drawing:

45 Fig. 1 is a perspective view of the invention, Fig. 2 is a longitudinal section through the invention showing the clamp in hair holding position with the operating head extended,

50 Fig. 3 is a vertical section on line 3—3 of Fig. 2, Fig. 4 is a view similar to Fig. 2 but with the clamp in hair releasing position with the operating head compressed,

55 Fig. 5 is a vertical section on line 5—5 of Fig. 4, and

Fig. 6 is an enlarged vertical section on line 6—6, Fig. 2.

Referring to the drawing, the body 60 has projecting therefrom two hair engaging curling elements 61 and 62, respectively, which may be separated by a slot 63. The body is provided with an inclined bore 64 to receive a shank 65 of clamp 66. A second inclined bore 67 receives a light compression spring 68 the left end of which as viewed in Fig. 2 bears against the part of the head 60 while the outer end bears against an upturned part 69 of the shank 65. The end of the shank may be bent back as at 70 to extend substantially parallel to the shank 65 and be received by a slot 71 formed in the head. The end 70 and slot 71 serve to guide the clamp and hold the same in proper operating position.

An operating head 75 slides over the cylindrical surface 76 of the head 60 and has passing therethrough a pin 77 which lies along the inner part of the upturned end 69 so that the latter is located between said pin and the outer hand engaging zone 78 of the head. The clamp may be in the form of a tongue as set forth in Fig. 2 and has a surface 80 to engage a similar surface 81 on the curling element 62, the clamp in the present instance being located within the curling element.

In normal position the spring 68 is expanded and holds the head in the relaxed or out position 30 shown in Fig. 2, and because of the fact that the axis of the bore 64 and the shank 65 are inclined with respect to the axis of the body and of the curling element the clamp will be in down position or against the clamping element considered as a whole. When the curler is to be used the operator will grasp the hair with the fingers against a rounded shoulder 85 and the palm against the zone 78 and give the head an inward movement against the action of the compression spring 68. This effects a relative inward movement of the clamp with respect to the axis of the curling element, spacing the curler and clamp as shown in Fig. 4, after which the ends of the hair to be curled may be introduced 40 through the slot 63 and located under the clamp. The head 75 may then be released, whereupon the spring will expand to move the head outwardly and the clamp downwardly or against the clamping element due to the inclined relation 45 already described relative to the bore 64 and clamp 65. The curler may be rotated to wind up the hair around the curling element and a bobbie pin inserted in the slot 63. Thereafter a slight inward motion of the head 60 relative to the 50 55

body or handle 68 will release the hair ends and the curler can be withdrawn.

From the foregoing it will be seen that I have provided a simple hair curler wherein the clamp and curling element move away from each other by a parallel motion, thereby insuring gripping of the ends of the hair throughout the length of the hair engaging parts of the curler. The relative separation of the clamp with respect to the curling unit is effected by means of an inclined surface which is oblique with respect to the body or handle, and the clamp moves with respect to the axis of the curling element. A light compression spring acts to return the clamp into holding relation with respect to the curling element, and furthermore there is a head to be manipulated preferably by the palm of one hand of the user and effective when pressed toward the curling element to move the clamp away from the said element to define a space or slot for the introduction of hair ends.

Having thus described my invention it will be seen that changes and modifications may be made therein by those skilled in the art without departing from the spirit and scope of the invention and I do not wish to be limited to the details herein disclosed, but what I claim is:

1. In a hair curler, a curling element, a clamping element, means operatively interposed between the elements to hold the clamping element against the curling element, and other means presenting a surface inclined with respect to the axis of one of the elements and along which the other element slides against the yielding means to move the elements away from each other when pressure is exerted on the clamping element.

2. In a hair curler, a holding body, a curling substantially cylindrical element projecting from the body, a clamp located within the curling element, means defining a sliding connection between the clamp and the body inclined with respect to the axis of the element, a plunger head operatively connected to the clamp, and yielding means interposed between the body and the clamp and tending normally to hold the latter against an interior surface of the curling element, said plunger head movable relatively to the body against the action of the yielding means to move the clamp away from said interior surface of the element.

3. In a hair curler, a curling element of substantially tubular form, a hair clamp located within and removable longitudinally with respect to the element, means defining a sliding connection between the element and the clamp inclined with respect to the axis of the element, a compression spring located between the element and the clamp tending normally to hold the clamp against an interior surface of the element, and a head slideable with respect to the curling element and in engagement with the clamping element, the spring normally tending to hold the head away from the curling element and said head being movable toward the curling element against the action of the spring to cause the clamp to move away from said curling element, the head when released being returned to normal position by the spring.

4. In a hair curler, a curling element of substantially tubular form, a hair clamp located within and movable longitudinally with respect to the element, means defining a sliding connection between the element and the clamp inclined with respect to the axis of the curling element, a yielding connection between the curling element and the clamp tending normally to hold clamp against an interior surface of the curling element, and means to move the clamp relatively to the curling element in opposition to the force exerted by said yielding connection and away from said interior surface due to the inclined sliding connection.

5. In a hair curler, a hair curling element having an elongated part around which hair may be wrapped and having a surface against which hair may be clamped, a clamping-element having a surface to clamp hair against said surface of the curling element, means defining a sliding connection between the curling and clamping elements and presenting relatively slidable surfaces extending in the direction of the length of said part, a spring interposed between the elements to resist relative movement of said elements in one direction, and means to slide one element on the other element against the opposition of said spring, certain of said surfaces being substantially parallel to said part of the curling element and other of said surfaces being inclined with respect to said part, to the end that sliding of the clamping element relatively to the curling element will cause separation of said surfaces on the clamping and curling elements to release hair.

6. In a hair curler, a curling element around which hair may be wrapped, a clamping element, said elements having mutually engaging surfaces between which the hair is clamped, means defining a sliding connection between the curling element and the clamping element and comprising surfaces inclined with respect to said engaging surfaces of the curling and clamping elements, resilient means interposed between the elements and acting to move said elements relatively to each other in a given direction to move the engaging surfaces toward each other, and means carried by one of said elements to slide said one element on the other element against the opposition of said resilient means opposite to said given direction and cause separation of the surfaces of said elements to release hair clamped by said elements.

7. In a hair curler, a curling element around which hair may be wrapped, a clamping element, said elements having mutually engaging hair clamping surfaces, said elements having other surfaces providing sliding connection between said elements inclined with respect to the clamping surfaces, resilient means to move one of the elements relatively to the other element in a direction to cause the clamping surfaces to approach each other, and means to slide one of said elements on the other element against the opposition of the resilient means in a direction to cause separation of the clamping surfaces by reason of said inclined surfaces.

GENNETTE UNWIN.
